UNITED STATES PATENT OFFICE.

THOMAS M. VAUGHAN, OF LISBON, OHIO, ASSIGNOR TO BENJAMIN F. BAIN, OF PITTSBURGH, PENNSYLVANIA.

MECHANICAL DANCING TOY.

1,407,451.

Specification of Letters Patent. Patented Feb. 21, 1922.

Application filed March 21, 1921. Serial No. 453,881.

To all whom it may concern:

Be it known that I, THOMAS M. VAUGHAN, a citizen of the United States, residing at Lisbon, in the county of Columbiana and 5 State of Ohio, have invented certain new and useful Improvements in Mechanical Dancing Toys, of which the following is a specification.

This invention has to do with improvements in mechanical dancing toys. One of 10 the objects of the invention is to provide a mechanical dancing toy which can be cheaply made from pressed sheet metal and from rods and other simple mechanical elements.

15 Another object of the invention is to provide a toy which shall be of attractive appearance and novel arrangement and in which the movements of the toy dancing figure are secured by momentum. In this connection, another object of the invention is to 20 make use of a momentum element which shall operate in the open and adjacent to the dancing figure so as to give a very novel and attractive appearance to the completed toy.

25 Other objects and uses of the invention will appear from a detailed description of the same, which consists in the features of construction and combinations of parts hereinafter described and claimed.

30 In the drawings:

Figure 1 shows a side elevation of a complete toy embodying the features of the present invention;

Fig. 2 shows a horizontal cross section 35 taken on the line 2—2 of Fig. 1, looking in the direction of the arrows but on enlarged scale. Fig. 2 is also a horizontal cross section taken on the line 2—2 of Fig. 3, looking in the direction of the arrows;

40 Fig. 3 is a vertical cross section taken on the line 3—3 of Fig. 2, looking in the direction of the arrows; and

Fig. 4 shows a detail fragmentary back face view of the dancing figure and the vertically oscillatable rod showing the manner 45 in which the figure is attached to the rod.

The base portion of the toy comprises an inverted cup 5 preferably having its lower edge 6 beaded as shown particularly in Fig. 50 3. A bracket 7 extends downwardly from the top 8 of the base member the lower portion 9 of said bracket being extended horizontally and then folded backwardly as shown at 10.

55 A shaft 11 is journaled in the top 8 of the

base member, and the lower end of said shaft 11 extends down through a hole 12 in the portion 9 of the bracket 7. The lower end 13 of the shaft 11 is preferably pointed and sets into a conical recess 14 in the end 10 60 of the bracket 7 which thus constitutes a foot bearing.

A block 15 has a bottom socket 16 adapted to receive the upper end 17 of the shaft 11, and to fit on the same sufficiently tight to 65 cause the shaft and the block to rotate together. Nevertheless, the block can be slipped off of the shaft without difficulty. Extending down from the block 15 are the arms 18 and 19 which reach down at an angle 70 and carry the weights 20 and 21 at their lower ends. These arms 18 and 19 are set into sockets 22 and 23 in the lower portion of the block 15 sufficiently tight to be ordinarily held in place, but they can be removed 75 from the block 15 without difficulty when so desired.

The block 15, arms 18 and 19, and weights 20 and 21 constitute a fly wheel having sufficient mass and inertia to drive the toy for a 80 reasonable length of time.

Extending through the top 8 of the base member and through the horizontal arm 9 of the bracket 7 is the vertically oscillatable rod 24. Connected to this rod is a stop arm 85 25 which is adapted to engage the shaft 11 or a sleeve on said shaft and thus the rod 24 is prevented from turning in the same direction as the shaft 11. A finger 26 is also connected to the rod 24, said finger carrying a 90 roller 27. On the lower end of the shaft 11 is a plate 28 which has one or more downwardly curved fingers 29 each of which constitutes in effect a cam adapted to pass under the roller 27 and lift the same as the shaft 95 11 is turned in the direction of the arrows in Figs. 2 and 3. Each time one of the cam surfaces passes beneath the roller 27, the rod 24 will be raised and then allowed to drop with a consequent vibrating movement. 100

A suitable figure 30 is mounted on the upper portion of the rod 24 so that said figure is caused to dance up and down as the toy is operated. This figure can be secured to the rod in any suitable manner as by means 105 of a clip 31 embracing the rod against the back side of the figure, said clip being held in place by one or more ears 32 which pass through the figure. If desired, a sleeve 33 may be placed on the shaft 11 between the 110

top 8 of the base member and the cam member 28 so as to keep the parts in proper relationship.

While I have herein shown and described 5 only a single embodiment of the features of my present invention, still I do not limit myself to said embodiments except as I may do so in the claims.

Where in this specification and the claims 10 to follow I use the expression "figure" or "dancing figure" or like expression, it will be understood that I do not limit myself to figures of the particular form or construction herein illustrated, but that I contemplate any suitable form or construction of 15 figure, whether it be a simulation of a human being, or animal, or inanimate conception.

I claim:

1. A mechanical toy comprising in combination a frame, a shaft journaled in the frame, connecting means on said shaft, a pair of radially extending momentum arms on said connecting means, a cam connected

25 to the shaft, and an oscillatable rod extending through the frame and working in conjunction with the cam, means for preventing rotation of said rod, and a figure carried by said rod, substantially as described.

2. A mechanical toy comprising in combination a frame, a vertical shaft journaled in the frame, connecting means on said shaft, a pair of radially extending momentum arms connected to said means, a cam member on the shaft, an oscillatable rod working through the frame, means on said rod working in conjunction with the cam, and a figure carried by said rod, substantially as described. 30

3. A mechanical toy comprising in combination a frame, a figure supporting means, a cam for imparting oscillatory movement 35 to the figure supporting means, a pair of radially extending arms mounted for rotation, and a connection from said arms to the cam for imparting rotary motion to the cam, substantially as described. 40

THOMAS M. VAUGHAN.
